WILHELM SCHEMMANN AND JEGOR BRONN, OF ROMBACH, GERMANY, ASSIGNORS TO ROMBACHER HÜTTENWERKE, OF ROMBACH, GERMANY, A CORPORATION OF GERMANY.

ELECTRIC FURNACE FOR MELTING AND LIQUEFYING FERRO-ALLOYS.

1,056,456.

Specification of Letters Patent.

Patented Mar. 18, 1913.

Application filed December 14, 1910. Serial No. 497,369.

To all whom it may concern:

Be it known that we, WILHELM SCHEMMANN, a citizen of the German Empire, and JEGOR BRONN, a subject of the Czar of Russia, residing at Rombach, in the Empire of Germany, have invented certain new and useful Improvements in Electric Furnaces for Melting and Liquefying Ferro-Alloys, of which the following is a specification.

10 The advantages of an addition of ferro-manganese in liquid form to the ingot-iron or mild steel to be deoxidized, have been pointed out heretofore by us in United States Letters Patent No. 915,488 obtained by us, and we have recommended for this purpose the employment of an electric furnace with pure resistance heating. It has been found, however, by continuous practical working of these furnaces that although 20 metal could be easily melted in the trough-furnaces therein suggested, that gradually a great deal of slag was collected in the melting trough which slag remained tough and had to be removed from time to time by 25 means of tools, which caused frequent interruptions in the working of the furnaces and by which the troughs were liable to be subjected to damage. When, however, it is attempted to melt ferro-manganese in an 30 electric arc-furnace such as is generally used for refining steel, a thick brown smoke begins at once to escape from the furnace owing to the combustion and evaporation of the manganese, and the loss of manganese which 35 takes place is so great that the re-melting of ferro-manganese becomes unprofitable.

It is well known that in electric arc-furnaces which are used in the refining of steel, the drop of the tension within the electric 40 arc, that is to say, when measured between the carbon-block and the metal bath, amounts to from 45-75 volts. It has been found however that, when the carbon electrode is lowered to such an extent that it just touches the 45 surface of the bath, and that when such a tension of the current is used, that the difference or drop of tension between the carbon and the metal bath amounts to only from 16-18 volts, and that this drop is below the elec- 50 tromotive counter-force of the arc, which is generally taken to be about 30 volts, it is possible to obtain, by the contact-resistance thus produced, an amply sufficient heating of

the melting bath without any noticeable loss of manganese taking place.

55 In the accompanying drawings, Figures 1 and 2 represent respectively a vertical longitudinal and a vertical transverse section of our improved electric furnace with three hanging electrodes for melting ferro-manganese and similar alloys, Figs. 3 and 4 represent respectively a horizontal section and a vertical longitudinal section of a modified two-trough combined electric furnace, Fig. 5, a horizontal section of a single trough 60 combined electric furnace adapted to be operated by a single-phase current, the vertical section of which is represented in Fig. 4, and Figs. 6 and 7 are respectively a vertical longitudinal and a horizontal section of a single trough or hearth electric furnace with a hanging and an inclosed electrode showing 65 our invention.

70 Similar letters of reference indicate corresponding parts throughout the several 75 figures.

A furnace intended for multiphase current, is illustrated in Figs. 1 and 2. It will be seen, that its construction is similar to that generally used for steel-furnaces, and 80 that like the latter, it can also be worked with an ordinary alternating current, that is to say, with only two electrodes. It is, however, as already stated, an essential condition that for obtaining the desired degree 85 of heat by contact-resistance instead of arc-heating, the drop or difference of tension between the electrode and the molten bath should not exceed the limits above stated.

90 The new observation that by contact-resistance, sufficient heat is obtained for remelting and keeping liquid ferro-manganese and the slag which forms on the same, induced the applicants to change the pure resistance-furnaces described in their U. S. 95 Patent No. 915,488 to a combined system in which resistance-heating is combined with heating by an electric arc of low tension, or which is the same by means of contact-resistance, so that the metal-bath forms the 100 heat-resistance in a trough-furnace in the well known manner, while the heating of the slag-covering is produced by the heat of an electric arc of low tension that is by contact-resistance. Such a combined furnace which 105 can be worked with a multiphase-current, is

illustrated in Figs. 3 and 4. It has the following advantages over the furnace shown in Figs. 1 and 2: 1. There is only one movable electrode suspended from the top, whereby the construction of the furnace is simplified. 2. The consumption of the expensive electrode-blocks is reduced to about one-third, and the work of replacing and regulating the electrode is greatly diminished. 3. It is much easier to heat at will the bath proper and the slag-covering, independently of each other, the metal bath being chiefly heated in the troughs by pure simple resistance heating, and the slag-covering in the hearth by contact-resistance. This heat-regulation is effected in the simplest manner by raising or lowering the level of the bath in the troughs, whereby the conductive cross-section of the metal bath, and in consequence thereof the strength of the passing current is modified.

As will be seen from Figs. 3 and 4, the two troughs 1 and 2 terminate in a spacious hearth 3 which is heated by the electrode 9. In the opposite closed ends of the troughs are blocks 4 of carbon or graphite. It has been found that ferro-manganese, unlike mild steel, does not dissolve the carbon. The electrode-blocks 4 are lowered into the closed ends of the trough and are therefore practically not worn out at all. Only as far as these carbon-blocks come into contact with the outer air, that is to say, at their upper portions, does a slow combustion take place as they are rendered incandescent by the heat of the current conducted through the same. In order to reduce this loss of carbon as much as possible and to obviate the complicated disconnection and re-connection of the conductors for the strong current, the connection is made in the following manner:

From the binding posts of the transformers, flexible cables lead to copper-bars 5, which surround a metallic body 6 that is cooled with water and mounted above carbon-plates interposed between the metallic body 6 and the carbon-block 4. To insure the intimate contact between the metallic body 6 and the carbon-plates, the former is pressed downwardly on the plates by means of a set-screw and an insulating part 8 arranged below the set-screw. The two troughs 1 and 2, and the carbon or graphite block 9 suspended above the hearth 3 of the same, are each connected with one of the phases a b c of the multiphase current employed. Fig. 5 is a cross-section of a similar furnace, which, however, is worked with a single-phase current.

In working with the furnace shown in Figs. 3 and 4, it is advisable to charge the furnace with ferro-manganese broken into small lumps. When, on the other hand, large pieces of ferro-manganese are introduced into the furnace, they dissolve but

very slowly and thus render it difficult to work the furnace continuously and in harmony with the working of the steel-plant proper. For that reason, it may be in certain circumstances more advisable to use in steel-plants a series of three furnaces of the type shown in Figs. 6 and 7, in place of the furnace shown in Figs. 3 and 4. Each of the three furnaces can then be connected, according to the condition of tension, either to two phases of the multiphase-current, that is to say, for instance: furnace 1 to the phases a and b , furnace 2 to the phases b and c , and furnace 3 to the phases a and c , or, when the tension is too great, to the two terminals belonging to one and the same phase. This series of three furnaces works simultaneously, but only they have to be charged and tilted intermittently. As even in the largest steel-plants there are hardly ever more than four converter charges made per hour, each of the furnaces has accordingly about three quarters of an hour's time in which the melting and heating of a fresh charge of ferro-manganese has to be effected.

The furnaces above described are also very suitable for melting other easily combustible or evaporable ferro-alloys especially when the same are rich in carbon.

We claim:

1. An electric furnace for melting ferro-manganese and similar alloys and keeping them in liquid state, which comprises a trough for the metal bath, an electrode above the trough and in contact with the metal bath at one end of the trough, a second electrode submerged in the bath at the opposite end of the trough, and a metallic current-conducting body held in contact with the submerged electrode.

2. An electric furnace for melting ferro-manganese and similar alloys and keeping them in liquid state, which comprises troughs for the metal bath united at one end so as to form a hearth, an electrode suspended above the united end of the troughs and in contact with the metal baths, electrodes located at the opposite ends of the troughs and submerged in the bath, metallic current-conducting bodies above the submerged electrodes, and means for pressing the metallic bodies into contact with the submerged electrodes.

3. An electric furnace for melting ferro-manganese and similar alloys and keeping them in liquid state, which comprises a trough for the metal bath, an electrode suspended at one end above the trough and in contact with the bath, an electrode submerged in the bath at the opposite end of the trough, a metallic current-conducting body above the submerged electrode, interchangeable carbon-plates between the submerged electrode and the metallic body,

and means for pressing the metallic body into contact with the carbon-plates.

4. An electric furnace for melting ferro-manganese and similar alloys and keeping them in liquid state, which comprises troughs for the metal bath united at one end so as to form a hearth, an electrode suspended above the hearth and in contact with the bath, carbon-blocks submerged in the opposite ends of the troughs, interchangeable carbon-plates above said blocks, metallic current-conducting bodies above the plates, current-conductors connected with

said bodies, and means for pressing the metallic bodies into contact with the carbon-plates for reducing the frequent disconnection and connection of the current-conductors.

In testimony, that we claim the foregoing as our invention, we have signed our names 15 in presence of two subscribing witnesses.

WILHELM SCHEMMANN.
JEGOR BRONN.
